UNITED STATES PATENT OFFICE.

ELIAS B. REQUA, OF JERSEY CITY, NEW JERSEY.

LAMP.

SPECIFICATION forming part of Letters Patent No. 297,847, dated April 29, 1884.

Application filed September 3, 1883. (No model.)

To all whom it may concern.

Be it known that I, ELIAS B. REQUA, a citizen of the United States, and a resident of Jersey City, in the county of Hudson and State 55 of New Jersey, have invented certain new and useful Improvements in Lamps, of which the following is a specification.

The invention relates to an improvement in lamps; and its object is to provide a lighting 10 device in which the drafts of air are effectually diffused and properly directed and their influence regulated to produce a regular brilliant pure flame capable of affording the maximum amount of light.

15 The invention will be readily understood from the detailed description hereinafter presented, reference being had to the accompanying drawings, in which—

Figure 1 is a central vertical section of a 20 lamp embodying the invention. Fig. 2 is a plan view, looking at a different side from that shown in Fig. 1, of the oil-font. Fig. 3 is a top view of same. Fig. 4 is a detached plan view of the wick raising and lowering devices.

25 Figs. 5 and 6 are top views of the deflector G and cone H, and Fig. 7 is a top view of the band X.

A denotes the oil-font, which is of suitable outline and of proper size to slip within the 30 sustaining-annulus B, spring-fingers C being provided on the exterior surfaces of the oil-font to engage the lower edge of the ring, whereby, when the font is inserted in place, the fingers will hold it in a set position. Af- 35 ter the font has been introduced in place and sustained by the spring-fingers C, it may be further secured by a set-screw, D, which passes through the ring B and finds a seat for its inner end in the cavity a, formed in the side of 40 the font. The ring B is supported between the lower ends of the bar forming the suspension-frame E.

Upon the upper central part of the oil-font A is arranged the wick-tube F, which is sur- 45 rounded by the deflector G and the foraminous cone H, the latter of which rests upon the horizontal arms I, extending radially outward from the wick-tube, while the former is sus- tained by the vertical flange J, which connects 50 the outer ends of the arms I.

Upon the deflector G is secured the annular

chimney-supporting rim L, which is appropriately adapted to receive the lower end of the globe or chimney N, and contains a line of perforations, O, at a point between the edge 55 of the chimney and the deflector G. The upper end of the chimney N protrudes into the lower part of the dome P, as indicated in Fig. 1.

Upon the upper edge of the ring B is ap- 60 plied the foraminous band K, which encircles the upper portion of the oil-font and base of the burner, and the purpose of the band K is to thoroughly diffuse the air prior to its passage through the line of apertures O to the 65 space within the chimney N, and through the spaces between the arms I to the inner side of the deflector G. The air which is fed to the flame from the lower part of the device enters through the foraminous band K, and thence 70 passes through the line of apertures O, the spaces between the arms I, and foraminous cone H. The air which reaches the flame is thus thoroughly diffused and effectually protected from the influence of outside drafts or 75 currents of air. In cases where the lamp is exposed to extreme drafts—such as in an open hallway or the saloon of a ferry-boat—it may be found desirable to secure over the forami- 80 nous band K an additional band of perforated material, X, and when this is to be employed I will usually construct it in two parts, hinged and adapted to be applied around the lamp, as indicated in Figs. 1 and 7.

Upon the upper edge of the foraminous band 85 K is provided the flange Q, in which rests the lower edge of the inverted-cone-shaped globe R, the upper edge of the globe terminating within the lower edge of the vertical perforated ring S, which depends from the reflector 90 T, which is adjustably secured between the sides of the flame E by means of the screws U and the slotted plates V, which are attached directly to the edge of the reflector. By loos- 95 ening the screws U the reflector may be moved vertically and secured in any set position by tightening the screws. The reflector T sup- ports at its center the dome P, which is per- forated, as indicated at X' and Y, and is held in position by set-screws x. In the part X of 100 the dome P are secured the cone-shaped de- flectors Z and Z', as indicated in Fig. 1. The

deflector *Z* extends slightly above the apertures in the part *X* of the dome, and is itself provided with apertures *b* below the line of the upper edge of the deflector *Z'*.

- 5 The wick may be raised and lowered in the wick-tube by means of the horizontal shaft *d*, having the usual toothed wheels upon its inner end in contact with the wick, and upon its outer end the gear-wheel *e*, in combination 10 with the vertical shaft *f*, having upon its upper end a gear-wheel, *g*, which meshes with the gear-wheel *e*, secured upon the horizontal shaft *d*, the lower end of the vertical shaft being provided with a suitable finger-wheel, *i*.
 15 Upon the lower edge of the ring connecting the outer ends of the horizontal arms *I* is secured a small staple, *n*, which encircles the shaft, *d*, and prevents its bending or disarrangement from proper relation to the vertical shaft *f*.

It will be observed that the vertical shaft *f* and the gear-wheels *e* and *g* are without the oil-font; and in order to permit of the introduction of the font carrying this mechanism 25 into the ring *B* without interfering with its operation, and without disturbing its parts, I have arranged on the inner side of the ring the vertical concave plate *m*, as indicated in Fig. 2. The vertical plate *m*, while preserving 30 the gear-wheels *e* *g* from contact with the edges of the ring *B*, operates also as a guide for directing the font *A* into the ring in such relation that the cavity *a* in the side thereof will come in proper position to receive the inner end of the set-screw *D*. The arrangement 35 of the shafts *d* *f*, with their gear-wheels, as described, admits of the wick being managed without removing the font from the annulus *B*.

For the purpose of providing for the expansion and contraction of the parts of the lamp adjacent to the wick-tube, I have provided a packing of rubber or other suitable material within the flange *Q*, and allow the globe *R* to rest therein. This packing also prevents the 45 jarring of the globe when the oil-font has been removed from the band *B* and replaced therein. A portion of the air which enters through the perforations in the ring *S* passes downward and is fed through the perforations *O* and between the arms *I*, while the remaining portion 50 encompasses the upper part of the chimney *N* and passes upward through the deflector *Z'* and

dome *P*. The passage of the air through the apertures in the dome *P* and deflectors *Z* *Z'* facilitates the movement of the current upward through the lamp, and the air passing around the sides of the inner deflector, *Z'*, has the effect of drawing the air from within over the edges of the said deflector and carrying it off through the apertures.

The arrangement of the draft-passages described prevents the formation within the globes of disturbing currents, and assists materially in the production of a regular white effective flame.

I reserve the right to use such parts of the device hereinbefore described as may be applicable for the purpose to the burning of gas.

What I claim as my invention, and desire to secure by Letters Patent, is—

1. In a lamp, the oil-font provided with the shafts and gear-wheels for raising and lowering the wick, in combination with the band *B*, having a concave vertical plate, *m*, substantially as set forth.

2. In a lamp, the oil-font, the wick-tube, arms *I*, foraminous cone *H*, deflector *G*, and rim *L*, provided with apertures within the line of the chimney, in combination with the band *B*, the foraminous band *K*, and inverted cone-shaped globe *R*, substantially as set forth.

3. The reflector *T*, the perforated ring *S*, and dome *P*, in combination with the inverted-cone-shaped globe *R* and the burner and chimney, substantially as set forth.

4. In a lamp, the oil-font, burner, chimney, globe, reflector, and dome, in combination with the ring *B*, foraminous band *K*, and detachable foraminous band *X*, substantially as set forth.

5. In a lighting device, the reflector *T*, globe, and burner, in combination with the bracket-frame *E*, screws *U*, and slotted plates *V*, the latter being secured to opposite sides of the reflector, and the frame being provided with apertures to receive the screws, substantially as specified.

Signed at New York, in the county of New York and State of New York, this 30th day of August, A. D. 1883.

ELIAS B. REQUA.
